UNITED STATES PATENT OFFICE

OSCAR CARLSON, OF EAST PROVIDENCE, RHODE ISLAND, ASSIGNOR TO DOLAN & BULLOCK, OF PROVIDENCE, RHODE ISLAND, A FIRM COMPOSED OF ARTHUR F. DOLAN, FRED A. BULLOCK, BOTH OF ATTLEBORO, MASSACHUSETTS, AND WILLIAM G. BENNETT, OF PROVIDENCE, RHODE ISLAND

CLASP

Application filed December 21, 1931. Serial No. 582,408.

This invention relates to a clasp of the type particularly adapted for securing a tie to the shirt of the wearer and commonly called a tie clip, and one of the objects of this invention is to provide a means for securing together the ends of two parts of one of the jaws of the clasp without the use of solder.

Another object of this invention is the provision of means for maintaining the ends 10 of the wire which form one of the jaws of the clasp in fixed relation without the use of solder.

A further object of this invention is the provision of a cap or sleeve member which 15 may receive the ends of a wire and be securely clamped thereabout to form a finished tip for these ends and at the same time secure them in desired relation.

A still further object of this invention is 20 the provision of a tie clip so folded from wire that the cap member for securing the ends together is spaced from the point of application of pressure to the fabric as it is moved in and out between the jaws of the clasp.

With these and other objects in view, the 25 invention consists of certain novel features of construction, as will be more fully described, and particularly pointed out in the appended claims.

30 In the accompanying drawing:

Fig. 1 is a top plan view of the clasp.

Fig. 2 is a bottom plan view thereof.

Fig. 3 is a side elevation thereof.

35 Fig. 4 is a plan view of one of the steps in the operation of forming the clasp.

Fig. 5 is a view similar to Fig. 4 after the step of placing the cap on the ends of the wires has been performed.

Fig. 6 is a perspective view of the cap.

40 Fig. 7 is a sectional view on line 7—7 of Fig. 5.

Fig. 8 is a plan view of a fragmental portion of a clip with a modified form of clamp member on the ends thereof.

45 Fig. 9 is a sectional view on line 9—9 of Fig. 8.

In the formation of tie clips it is desirable to provide a clasp at a minimum expense consistent with good appearance and maximum usefulness and durability. In a wire

clip, in order that the ends of the wire may provide a finished appearance and also not abrade the fabric or person of the user, the ends are often soldered together. Soldering, however, is an expensive operation, and in order to provide a securing means for the ends and at the same time finish the ends and provide an attractive appearance I have formed a member which may embrace the end portions of the wire and by suitable deflection be held in close frictional contact therewith, thus holding the ends together in desired position without the use of solder; and the following is a detailed description of the present embodiment of this invention illustrating the preferred means by which these advantageous results may be accomplished.

With reference to the drawing, there is illustrated in Fig. 4 a length of wire which is 70 folded at 10 to provide arms 11 and 12 which are suitably outwardly deflected as at 13 and 14 with their ends turned inwardly as at 15 and 16. These ends are then secured together as illustrated in Fig. 5 by placing a 75 cup shaped cap 17 over the ends as illustrated in Fig. 5, and deflecting the cap 17 inwardly as at 18 to closely fit about the curved wire end portions 15 and 16 of the wire, and I also compress the cap as at 19 80 deflecting the stock thereof and also the stock of the wire as at 20 inwardly so that the cap member 17 is securely held in position on the end portions 15 and 16. In this construction, the formation of the wire is such that the ends 85 15 and 16 will contact with each other prior to the contact of the neck portions 21 and 22.

In some instances, however, instead of turning the ends inwardly upon themselves, as illustrated at 15 and 16, I slightly curve the 90 end portions as in 23 and 24 in Fig. 8 and provide a different shaped cap 25 to receive the ends 23 and 24 and be secured thereto by deflecting the stock of the cap and also the stock of the end portions 23 and 24 inwardly 95 as above set forth and as illustrated at 26 to securely hold this cap in position.

After securing the ends by means of this cap member the clasp is completed by folding the same upon itself as at 27 to provide jaws 100

28 and 29, the jaw 29 having a portion 30 in contact with the jaw 28 at a single point, while the end portion of this member 31 is bent upwardly from this point of contact to provide a mouth 32 for the reception of the fabric. The bent upward portion 31 carries the securing cap member 17 and removes it from a position which may contact with the fabric, but as its closed end 33 in the showing of Figs. 1 to 7 inclusive is innermost of the clasp, a smooth surface is provided in case the same should contact with the fabric, while its edge 34 is outermost and in a position where contact with the fabric into or out of the clasp would be doubtful, and at the same time a better appearance is provided.

The foregoing description is directed solely towards the construction illustrated, but I desire it to be understood that I reserve the privilege of resorting to all the mechanical changes to which the devise is susceptible, the invention being defined and limited only by the terms of the appended claims.

I claim:—

1. A clasp comprising a pair of jaws, one of said jaws having a plurality of portions with their ends in adjacency, and a cup member receiving the end portions and holding them in fixed relation, said cup member being flattened and deflected inwardly to closely embrace and frictionally contact with said end portions.

2. A clasp comprising a pair of jaws, one of said jaws having a plurality of portions with their ends in adjacency, and a member receiving the end portions and holding them in fixed relation, said end portions being recessed and said member having portions extending into said recesses to hold the member in assembled position.

3. A clasp comprising a pair of jaws, one of said jaws having a plurality of portions with their ends in adjacency, and a cup member receiving the end portions and holding them in fixed relation, said cup member being deflected inwardly to closely embrace and frictionally contact with said end portions, said end portions being recessed and said member having portions extending into said recesses to hold the member in assembled position.

4. A clasp comprising a pair of jaws, one of said jaws having a plurality of separate portions with their end portions turned in and contacting with each other and a member receiving said turned-in end portions and holding them in contact with each other.

5. A clasp comprising a pair of jaws, one of said jaws having a plurality of separate portions with their end portions turned in and contacting with each other and a cup member receiving said turned-in portions and holding them in contact with each other, said cup member being deflected inwardly to

closely embrace and frictionally contact with said end portions.

6. A clasp comprising a pair of jaws, one of said jaws having a plurality of separate portions with their end portions turned in and contacting with each other and a cup member receiving said turned-in end portions and holding them in contact with each other, said cup member being deflected inwardly to closely embrace and frictionally contact with said end portions, said end portions being recessed and said member having portions extending into said recesses to hold the member in assembled position.

7. A clasp comprising a length of wire folded upon itself with its two ends turned in and in adjacency and again folded to provide contacting jaws, and a cup member receiving and embracing the end portions of said wire and holding them in fixed relation with the edges of the cup facing outwardly, the end portion of the jaw carrying said cup member being bent away from the other jaw to provide an entrance mouth for said clasp and at the same time space the edge of said securing member from contact with the fabric inserted between said jaws.

8. A clasp comprising a length of wire folded upon itself with its two end portions folded inward and in adjacency and again folded to provide contacting jaws, and a cup member having a closed end receiving and embracing the end portions of said wire and holding them in fixed relation, said cup member having its closed end inwardly and its other end outwardly with respect to said clasp and said cup member being inclined with reference to the opposite jaw and with its closed end nearer thereto.

In testimony whereof I affix my signature. 105
OSCAR CARLSON.
